CLAIM

The ornamental design for a cup lid with handle and dual drinking structures, as shown and described.

DESCRIPTION

FIG. 1 is front elevation view of a cup lid with handle and dual drinking structures, showing our new design;

FIG. 2 is a rear elevation view thereof;

FIG. 3 is a left side elevation view thereof;

FIG. 4 is a right side elevation thereof;

FIG. 5 is a top plan view thereof;

FIG. 6 is a bottom plan view thereof;

FIG. 7 is a front, left side, and top perspective view thereof;

FIG. 8 is a front, right side, and top perspective view of an alternative configuration of the cup lid with handle and dual drinking structures, when one drinking structure is in an opening state;

FIG. 9 is a front, right side, and top perspective view of another alternative configuration of the cup lid with handle and dual drinking structures, when the other drinking structure is in an opening state; and,
FIG. 10 is a left side and bottom perspective view of the cup lid with handle and dual drinking structures from FIG. 1.
